EUGENE G. McGLAUFLIN,
INVENTOR.

BY *R. Conright*
ATTY.

UNITED STATES PATENT OFFICE.

EUGENE G. McGLAUFLIN, OF PORTLAND, OREGON.

HEAT-RADIATING DEVICE.

1,422,282.

Specification of Letters Patent. Patented July 11, 1922.

Application filed March 17, 1920. Serial No. 366,504.

To all whom it may concern:

Be it known that I, EUGENE G. McGLAUFLIN, a citizen of the United States, residing at Portland, in the county of Multnomah 5 and State of Oregon, have invented a new and useful Improvement in Heat-Radiating Devices, of which the following is a specification, reference being had to the accompanying drawings.

10 My invention relates to heating devices for dry-kilns as a class.

The object of my invention is to provide a heating device for a dry-kiln arranged in a manner whereby substantially the same 15 body of air in the kiln may be caused to circulate in heated condition for drying purposes and when charged or saturated with exudations from the drying material to be thereafter quickly cooled to deposit its said 20 content and be again thereafter used for drying. Also a convenient arrangement of the heating device whereby it may be quickly installed and repaired with economy. These objects, as well as other advantages, 25 I attain by the construction, combination and arrangement of parts illustrated in the accompanying drawings which form a part hereof.

Fig. 1 is a cross sectional elevation of the 30 kiln.

Fig. 2 is a plan view of tracks and a section of piping below same.

Fig. 3 is a sectional elevation of a longitudinal part of the kiln near the ceiling on 35 the line 3—3 in Fig. 1.

Fig. 4 is an enlarged sectional view of vertical spacing wall or partition.

Like characters refer to like parts in all the views.

40 A rectangular structure of desired dimensions is provided. It is intended that the wooden construction shall be of culed material for economy thereof. A foundation preferably of artificial stone, is placed. A 45 low, wooden base wall 5 is erected on the foundation, and above this the outer walls 5' are of thin metal, preferably corrugated material. On the inside of the vertical studing which supports the walls, a wooden 50 spacing wall 6 extends from a desired height above the foundation to a desired distance from the ceiling. This is to make hollow walls for the distance indicated. The wall 6 is of double thickness, with a material 7, 55 which is a non-conductor of heat, between the sheeting of said wall. The ceiling 8

is of the same construction as the wall 6. In the forward end of the structure for a short distance rearwardly, a part of the walls 6, indicated as 9 in Fig. 3, extends 60 upwardly to a joining position with the ceiling 8. Longitudinally of the structure, a series of track rails 10 are secured upon frames 11 below. A heat supply pipe 12 extends from an outside heating source, 65 within the structure to a connection with a pipe 13 extending at a convenient distance from and parallel with one wall 6. On the opposite side a pipe 14 extends longitudinally along the floor of the structure parallel with, at a little distance from, and below the bottom of the opposing wall 6. The pipe 14 has a discharge pipe 15 extending from it and without the structure. 70 A series of pipe batteries 16 are arranged 75 one above the other between the rail tracks and floor. Each of the batteries has a series of horizontal pipes 17 extending from connections with the respective pipes 13 and 14 inwardly at an angle to a connection with each other at their opposite ends. Joining means 18 are placed in the pipes 17 to facilitate placing them in position and taking them apart. Drain outlets 19 are arranged from below the hollow wall 80 space outwardly of the structure. Trucks 20 are shown in position on the tracks, bearing material in the process of drying.

It will now be seen that when the tracks are filled with material laden trucks and 90 heat is admitted to the pipe system, the heated air which rises from below the series of trucks in the forward end cannot follow a course over the tops of the inside walls 6, as they are there joined to the ceiling as 95 shown in Fig. 3, and the air remains longer in that portion of the structure, thereby supplying a non-circulating hot air medium which provides a steadier heat. Thus the liquids in the material are drawn therefrom and absorbed by the heated air in a manner to prevent the common checking or case hardening therein. The material on the first series of trucks introduced into the structure will always have this first 100 treatment. Thereafter the trucks are pushed forwardly and in the remaining part of the structure the heated air follows a course upwardly through the material, thence being deflected by the ceiling over the walls 105 6 and downwardly through the hollow wall spaces between the walls 5 and 6. The 110

air, being then charged with the liquids or substances absorbed from the drying material, engages the thin outer wall 5, which being cooled by the outer atmosphere, the absorbed liquids, etc., are thereupon condensed and trickle downwardly, to escape through the outlets 19, while the same air, with its partial heat, continues in and about the heating pipes, and follows 10 the same circulating course as shown by the arrows in Fig. 1, with the same results as described. It is also intended that the pipes 17 shall be inclined in a manner to allow them to drain effectually, in the course 15 shown by the arrows in Fig. 2. This is an important feature, as there are no cocks to manipulate, requiring time and strict attention. The arrangement of the lateral pipes at an angle supplies a greater heating 20 surface and the end connections and joining means 18 provide a method for setting up and taking down any lateral without interference with the others, as all are independent. The arrangement of the laterals 25 facilitates caring for the pipe when contraction or expansion occurs in any part. It is possible to use all iron or steel in the metal parts, which makes a cheap construction. The combination of condensa-

tion with the same body of circulating air 30 is new and useful, and saves expense in heat production. The placing of the pipes one above the other allows small refuse to fall to the floor and prevents fire risk. The pipe and connections are all of common type 35 which is likewise economical.

I claim—

A heat radiating device, wherein is combined, a feed pipe, a discharge pipe positioned below the plane of the feed pipe, 40 and a series of batteries of lateral pipes, each lateral pipe being independent and extending from a connection with the feed pipe at an angle and inclination, to a connection, thence in a reverse angle and inclination to a connection with said discharge pipe, each of said lateral pipes being arranged to allow effective drainage through the same, without auxiliary means therefor, and also to allow each lateral pipe and 50 sections thereof to be secured, adjusted, or removed between connections, independently of other pipes in said radiating device.

EUGENE G. McGLAUFLIN.
